UNITED STATES PATENT OFFICE.

OLIVER B. KAISER, OF RAMONA, OHIO, ASSIGNOR OF ONE-THIRD TO WALTER S. LUDLOW AND ONE-THIRD TO WALTER S. LUDLOW, JR., BOTH OF CINCINNATI, OHIO.

ALARM SYSTEM.

1,073,582.

Specification of Letters Patent. Patented Sept. 16, 1913.

Application filed October 17, 1910. Serial No. 587,612.

To all whom it may concern:

Be it known that I, OLIVER B. KAISER, a citizen of the United States, residing at Ramona, in the county of Hamilton and 5 State of Ohio, have invented new and useful Improvements in Alarm Systems, of which the following is a specification.

My invention relates to alarm signal systems primarily adapted in the supervision 10 of automatic sprinkler systems.

One of the objects of my invention is to provide an alarm signal system indicating or transmitting a series of separate and distinctive alarms or signals of abnormal conditions of each of the various appliances of 15 a sprinkler system under supervision with means for indicating or transmitting a separate and distinctive alarm or signal upon restoration to normal of each of such abnormal conditions without interference or 20 normal conditions without interference or confusion of signals.

Another object of my invention is to provide an alarm system for automatically indicating or transmitting a series of separate 25 and distinctive signals or alarms, indicative of abnormal conditions of the particular features or appliances under supervision with means for indicating a separate and distinctive alarm or signal upon restoration of the 30 entire system to normal.

Various other features of my invention will be more fully set forth in the description of the accompanying drawings forming a part of this specification, in which—

35 Figure 1 is a diagrammatic view of my alarm signal system in complete form. Fig. 2 is a diagrammatic view illustrating the system of wiring of the normal signal and its control.

40 The general features of my system are disclosed and described in Letters Patent issued to me February 1, 1910, No. 948,055, relating to the control of abnormal signals and therefore I will herewith only briefly 45 describe the same.

In the description following, I shall term each appliance under supervision as a controller, provided with means for making and breaking an electric circuit or circuits, 50 either manually or automatically according to the nature of the appliance applied to, and operative in connection with a valve, pressure, temperature, water level gaging apparatus, water flow and the like appli-

ances requisite for a complete supervision 55 of a sprinkler system.

In general the system is maintained under constant test from the central or supervisory station in normal condition directly with each of the controllers, independent of the 60 signal indicating or transmitting mechanism.

In a movement to abnormal of any one or more of the particular features under supervision, a controller thereof is operated, 65 breaking two circuits, one the test line between controllers and central station and a second to the signal mechanism of such abnormal controllers, each controller having its independent signal mechanism. Each 70 signal mechanism comprises a magnet and an armature lever, controlling a series of electric circuit make and break means, a lock magnet and its armature lever for locking the main armature lever against actuation 75 during the transmission of a preceding signal, and means for controlling the movement of the main armature lever for producing the various actuations, for transmission and non-interference of signals, as is 80 fully described in my aforesaid Letters Patent.

1, 2, 3, 4 and 5 represent the controllers of the various particular features under supervision.

85 1^a, 2^a, 3^a, 4^a and 5^a represent signal transmission devices for the respective controllers 1, 2, 3, 4 and 5. In each set 6 represents a main magnet, 7 an armature lever therefor, which, in step movement, controls a series 90 of electric circuits or circuit make and break devices.

8 represents a circuit controlling or switch mechanism, actuated by the armature lever 7 for completing the main or metallic signal 95 circuit to the signal break wheel n.

9 represents the switch mechanism for the ground signal circuit and 10 the switch mechanism for lock magnets, 11, switch mechanism for the final closing of the main 100 signal circuit after the transmission of a signal.

12 represents the lock magnet coil and 13 the lock armature lever adapted, when the magnet coil 12 is energized, to engage the 105 armature lever 7 within predetermined limits of its movement to prevent further movement thereof, a provision to prevent the

switch mechanism, of two or more signal transmitting devices, closing simultaneously.

14, 15 represent wires in connection with the source of electric supply 16.

5 The following plan of wiring is duplicated for each controller and its respective signal transmission mechanism: 17 represents a wire in connection with the supply wire 15, and one pole of the magnet 6. 18 70
10 represents a wire in connection with the opposite pole of the magnet coil 6 and switch mechanism 19 of the controller 1. 20 represents a wire connected with the switch mechanism 19 and supply wire 14. Under normal 75 condition of the system of each particular feature under supervision, the controller thereof occupies a position to maintain the switch mechanism closed, completing the circuit to the magnet 6, energizing 80
20 the same. A normally closed circuit is maintained as the same is a standard in commercial use, it is obvious, however, that the same can be operated on other types of circuits as far as the features of this invention 85
25 are concerned. Therefore, with a closed circuit normally the armature levers 7 will be attracted to their respective magnet coils.

The lock magnets of the series are in series 90 wiring with each other, and their controlling 95
30 switch mechanism is in multiple wiring. Therefore when the switch mechanism 10 of any one of the series is closed all the lock magnet coils of the series will be energized, attracting their respective armature levers. 100
35 The wiring preferably is as follows: 21 represents a wire in connection with supply wire 15 and connected in multiple to one pole of all the switch mechanism 10, and 22 represents a wire connecting the opposite 105
40 poles of the switch mechanisms 10 in multiple, with said wire leading to and connected in series with the lock magnets 12. The last magnet coil of the series is connected by a wire 23 to the supply wire 14. 110
45 thus any one of the switches 10 when closed will complete the circuit to all lock magnets and operate their respective armature levers 13.

The armature levers 7 of the series are, 115
50 when released, controlled in their movement by a cam or guide wheels constructed and arranged, or time controlled relative to each other, so that no two armature levers 7 can simultaneously occupy a position to close 120
55 the switch 8, 9 and 10.

A type of mechanism for controlling each armature lever to produce the step movements is shown and described in my former patent aforesaid. This comprises a cam or 125
60 guide wheel for each armature lever 7, with all preferably mounted upon and fixed to rotate with a single shaft, driven by a single source of motive power. The guide wheels are so arranged as to permit its respective 130
65 armature lever to swing to a second position,

or position closing the switch mechanisms 8, 9 and 10, at only a predetermined point in each rotation thereof, and with this point in each of the guide wheels of the series set in staggered relation to each other, making it impossible, for two armature levers, to simultaneously occupy such switch closing position.

The signal transmitting wiring is substantially the same as that disclosed in my said 75 patent, and therefore it is thought further detail description of operation is unnecessary.

The general arrangement of my present invention can be more clearly understood 80 by reference to Fig. 2, in which all other features are eliminated.

The armature levers 7 of the series are each provided with a switch mechanism 24, in which one pole of each is connected in 85 multiple with a wire 25 to the magnet coil 26, of the normal signal transmitting mechanism 27.

29 represents a wire connecting the opposite pole of magnet coil 26 to the supply 90 wire 15. 30 represents a wire connecting the opposite poles of the switch mechanisms 24 of the series, in multiple with the supply wire 14. Thus, when any one of the said switches 24 is closed, completing the circuit, the magnet coil 26 will be energized attracting its armature lever and thereby close the switch mechanism 31, which in this instance controls the source of electric supply to the motor 32.

The armature lever 7, of the normal signal transmitting mechanism 27, operates in substantially the same manner as the armature levers 7 of the abnormal transmitting mechanism of each particular feature under 105 supervision as heretofore described. It is also controlled in its movement when released by its magnet coil by a cam or guide wheel fixed to the same shaft as the guide and signal indicating wheels of the transmitting mechanisms 1^a, etc., of the series, to produce step-like action and operate various switch mechanism at proper intervals. It assumes a reverse position from the abnormal indicating or transmitting mechanism, in that, when any of the magnet coils 6 of the series are deenergized, coil 26, will be energized, and remain so until all of the magnet coils of the series are brought to normal, or energized. The switch mechanisms 24 of the series remain closed as long as its respective armature lever is released from its magnet influence.

The switch can close the circuit to the magnet coil 26 upon the first step movement, 125 or release of its armature lever and remain closed during the successive step movements of said lever, which is the operation in this instance, wherein the armature lever of the normal signal transmitting mechanism con- 130

trols the motive power circuit. It is obvious, however, without departing from the features of my invention, that a motor controlling switch can be operated by each of the armature levers of the series, both normal and abnormal transmitting mechanisms, whereby upon any armature release the motor circuit will be completed, thereby rotating the shaft containing the signal and guide wheels, and further the motor circuit can be cut-off when any one or more of the armature levers come to a final released position, after signal transmission. In the wiring plan illustrated, the motor circuit controlled by the position of the armature lever of the normal signal transmitting mechanism 27, is not broken until after restoration of abnormal conditions of the system under supervision and after the normal signal has been transmitted. As these devices and systems must comply with conditions made by fire insurance companies or underwriters, differing in localities, and meet conditions also of a general organization, its laboratory regulations and tests, therefore the method of motor control is optional, but the motor must be in commission immediately when the system becomes abnormal in any one or more of its particular features under supervision, and upon restoration for the normal signal transmission.

As the armature lever 7 of the normal signal transmitting mechanism 27, is under similar step control as the abnormal signal transmitting mechanism it is likewise provided with similar switch mechanism for controlling the ground and lock magnet circuits, namely switch mechanism 9 and 10.

The system is maintained under test in substantially the same manner as illustrated in my said prior patent, and as is illustrated herewith, and therefore the description as to details is herewith omitted. In general however, each controller of the series is wired in series with the main or metallic signal circuit, leading to the central or signal receiving station, maintaining a test direct with the controllers which would be indicative of an open line if a controller became abnormal, and the transmitter failed to operate. The switch mechanism 11 of each armature lever 7 short circuits such break after a signal transmission, placing the signal circuit again under test through the switch mechanism of the transmitting mechanism in place of the controller. Thus the armature lever of the normal transmitting mechanism 27, is not provided with or controls a main or metallic signal circuit switch, but only with the ground signal circuit switch, and only one kind of signal is transmitted for normal indication, instead of two kinds of signal of duplicate indication for abnormal, namely metallic and ground; for the reason that the main line

would have to be again opened or broken. One kind of normal signal is usually sufficient. Therefore by operating in this manner the main circuit is not completed through any of the transmitting mechanisms, in normal condition of the system, but only through the controller thereof. It is obvious, however, that switch mechanism may be controlled by the armature lever of normal transmitting mechanism 27, whereby such main line or closed circuit signal can be transmitted without departing from the features of my invention.

It is quite obvious that various modifications can be made without departing from the features of my invention, but I believe I am the first to provide a system automatically indicating or transmitting a series of separate and distinctive signals, indicative of abnormal conditions of the features or appliances under supervision and indicating or transmitting a separate and distinctive signal or alarm upon restoration of the entire system to normal without interference or confusion of any of the signals.

Having described my invention, I claim:—

1. In an alarm system, one or more controllers of a system under supervision, independent alarm signal mechanism for each controller, means governed by the abnormal conditions of the controllers for automatically transmitting an independent signal for each controller, locking out the transmission of a signal or signals of abnormal controllers during the transmission of one of them, and means for automatically transmitting a signal upon restoration of all controllers to normal.

2. In an alarm system, one or more controllers of a system under supervision, alarm signal mechanism, means for setting said alarm signal mechanism into operation after one or more of said controllers become abnormal, means for automatically, serially effecting a signal transmission of independent signals for each abnormal controller, and means for automatically transmitting a signal upon restoration of all controllers to normal.

3. In an alarm system, one or more controllers of a system under supervision, an alarm circuit maintained under test condition with said controllers in normal condition thereof, and means governed by the abnormal conditions of the controllers for automatically, serially transmitting an independent signal for each abnormal controller, maintaining the alarm circuit in transmitting and under test condition during the abnormal condition of the controllers, and means for automatically transmitting a signal upon restoration of the system to normal indicative thereof.

4. In an alarm system, one or more features under supervision, means for auto-

4

matically indicating or transmitting a separate and distinctive signal or alarm indicative of abnormal condition of each feature of the series under supervision and means indicating a separate and distinctive signal or alarm upon restoration of the entire system to normal.

5. In an alarm system, a series of devices responsive to prevailing condition of a system under supervision, signal devices con-

trolled thereby indicative of distinguishable signals for each change of condition, and a signal device responsive to the condition of said signal devices indicative of a distinguishable signal of restoration to normal of all the devices. 15
